WILLIAM ALONZO SCOTT, JOHN JONES KING, AND CHARLES JAMES BROWN, OF CONSUL,
ALABAMA.

LIFTING-JACK.

No. 890,459.

Specification of Letters Patent.

Patented June 9, 1908.

Application filed October 31, 1907. Serial No. 400,049.

To all whom it may concern:

Be it known that we, WILLIAM A. SCOTT, JOHN J. KING, and CHARLES J. BROWN, citizens of the United States, and residents of 5 Consul, in the county of Marengo and State of Alabama, have made certain new and useful Improvements in Lifting-Jacks, of which the following is a specification.

Our invention is an improvement in lifting 10 jacks and consists in certain novel constructions and combinations of parts hereinafter described and claimed.

Referring to the drawings forming a part hereof—Figure 1 is a perspective view of the 15 improvement in operation. Fig. 2 is a side view partly in section, and Fig. 3 is a detail perspective view of the base.

The present embodiment of our invention 20 comprises a base 1 of substantially U-shape, the base being adapted to rest upon the ground, and to receive the end of the tie 15 between the arms 2 thereof.

The body portion of the base is recessed as 25 at 5, and the upper face is slotted as at 6, for a purpose to be presently described, and that portion of the body adjacent to the arms is rounded as at 7 to form a seat, a pair of spaced lugs 4 being arranged at each end of the rounded portion.

30 The one end of a plate spring 8 is received within the recess 5, being retained in place by a set screw 10, and the other end of the plate spring is provided with spaced bearings 9, between which is pivotally mounted a vertical arm 11, provided on one side with a plurality of notches 12, and at its bottom with a lug 16 for limiting the swinging motion of the arm with respect to the plate spring.

A pinch bar 13 is provided on its lower face 40 with a plurality of recesses 14, arranged to fit the rounded portion 7 of the base and to rock thereon, as shown in Figs. 1 and 2, and the notches 12, are adapted to receive the free end of the bar when the tie has been elevated into contact with the rail, whereby to retain the tie in such position.

In operation, the jack is placed in the position shown in Figs. 1 and 2, and the point of the bar is inserted beneath the tie, with one 45 of the recesses in the bar engaging the rounded portion 7 of the base. The bar is now rocked until the tie is in engagement with the base of the rail, when the handle of the bar is engaged with one of the notches in the ver-

tical arm, thus retaining the tie in the desired position during the driving of the spikes. 55

The jack is simple in construction and economical, and is also easily handled, since it may be made comparatively light, there being no great strain upon any part of the same. 60 The plate spring 8, permits the tie to give somewhat during the operation of driving the spike, yet returns the tie to its original position as soon as the force of the blow is passed. 65

When assembling the improved jack, the end of the plate spring is inserted in the recess, and the screw 10 is turned into position, the slot 6 being provided to permit access to the screw. 70

While we have described the pinch bar as being provided with recesses for engaging the seat on the base, it is obvious that an ordinary pinch or claw bar might be used. 75

We claim—

1. A lifting jack comprising a U-shaped base, the arms of which are adapted to receive therebetween the end of a tie, the body portion of the base being provided with a recess and with a rounded portion having at each end thereof a lug, a plate spring having one end received in the recess and the other provided with spaced bearings, a notched arm pivoted between the bearings and provided with a lug for limiting the swinging motion thereof with respect to the spring, and a pinch bar resting between the vertical lugs, and provided with a plurality of recesses for engaging the rounded portion of the base. 90

2. A lifting jack comprising a base provided with a recess and with a rounded portion having at each end thereof a lug, a plate spring having one end received in the recess and the other provided with spaced bearings, a notched arm pivoted between the bearings and provided with a lug for limiting the swinging motion thereof with respect to the spring, and a pinch bar resting between the vertical lugs, and provided with a plurality of recesses for engaging the rounded portion of the base. 95

3. A lifting jack comprising a base provided with a recess and with a rounded portion having at each end thereof a lug, a plate spring having one end received in the recess, a notched arm pivoted to the end of the spring and provided with a lug for limiting 100

- the swinging motion thereof with respect to the spring, and a pinch bar resting between the vertical lugs and provided with a plurality of recesses for engaging the rounded portion of the base.
4. A lifting jack comprising a base provided with a seat, a plate spring having one end connected with the base, a notched arm pivoted to the other end of the spring, and a pinch bar provided with a recess for engaging the seat on the base, the end of the bar being adapted for engagement by the notches of the arm.
5. A lifting jack comprising a base provided with a seat, a plate spring connected with the base; a notched arm connected with

the spring, and a pinch bar having a recess for engaging the seat and adapted to be engaged by the notches of the arm.

6. A lifting jack comprising a base provided with a seat, a plate spring connected with the base, a notched arm connected with the spring, and a pinch bar for engaging the seat and adapted to be engaged by the notches of the arm. 20
